(57) **CLAIM**

I claim the ornamental design for fluid manifold, as shown and described.

DESCRIPTION

FIG. 1 is an enlarged perspective view of the fluid manifold showing our new design;

FIG. 2 is a rear edge view thereof;

FIG. 3 is a right edge view thereof;

FIG. 4 is a front edge view thereof;

FIG. 5 is a left edge view thereof;

FIG. 6 is a bottom view thereof; and,

FIG. 7 is a top view thereof.

The broken lines in the drawings are included for the purpose of illustrating elements of the fluid manifold and form no part of the claimed design.
